VALVE GRINDER

Frank T. Sweigart, Port Washington, N. Y.

Application March 7, 1936, Serial No. 67,574
Renewed January 7, 1939

3 Claims. (Cl. 51—185)

This invention relates to a device for grinding valves and valve seats of motors and other machines in situ and is characterized by simplicity, cheapness and convenience in use. So far as is known no grinding device or the like has been heretofore provided which might be applied to valves without either removing the valves or at least changing the normal assembly of parts.

10 The principal object of the invention is to provide a device by which valves and valve seats might be ground without removing the valve or disturbing the normal relationship of associated elements. A further object of the invention is to provide a device for the purpose indicated which has a grinding element that may be readily slipped into operative relation to the valve or valve seat to be ground when the valve is elevated from its seat by its operating mechanism. 15 A further object of the invention is to provide a device for the purpose indicated which has a grinding element that may be readily slipped into operative relation to the valve or valve seat to be ground when the valve is elevated from its seat by its operating mechanism. 20 A further object of the invention is to associate with the aforesaid grinding elements means by which it may be rotated to accomplish its grinding function. Still another object of the invention is to provide simple means for connecting and disconnecting the grinding element from the means by which it is rotated. A further object of the invention is to provide a grinding element which may have on its faces a suitable abrasive material whereby upon rotation of the grinding 25 element a valve and its seat may be ground simultaneously. Still another object of the invention is to provide a simple element for the purpose set forth whose shape and size may adapt it for grinding the particular valve and seat with which 30 it is to be used.

In accordance with the invention the grinding element no matter what shape is so formed as to permit it to be slipped under the valve to be ground, a central opening being provided to receive the valve stem. With a grinding element of suitable form and dimensions thus placed between the valve and its seat a second element is placed over the valve and engaged with the grinding element, such second element being operatively connected to a suitable source of power by means of which the grinding element may be rotated to grind the valve in situ and, if desired, the valve seat.

These and other objects and advantages will 50 appear more fully hereinafter in connection with the description of the form of the device illustrated in the drawing by way of example and in which:

Figure 1 is a view in vertical section of a fragment of a motor showing a conventional valve

with its operating cam and the relation thereto of the improved device with the valve raised.

Figure 2 is a view similar to Figure 1 with the valve lowered onto the grinding element and the power transmission element engaged therewith.

Figure 3 is a view in plan of one form of power transmission element.

Figure 4 is a view in transverse section through the member shown in Figure 3 and taken on the plane indicated by the line 4—4 and looking in 10 the direction of the arrows.

Figure 5 is a view in side elevation of one section of a grinding element where the latter is of sectional rather than unitary form.

Figure 6 is a view in plan of the type of grinding element shown in Figure 5.

Figure 7 is a view in section showing a unitary grinding element in operative relation to a valve and its seat.

For the purposes of this description there is 20 illustrated at *a* a valve having a tapered seat *b* in the engine block *c*. The valve is reciprocated in the usual manner by a cam *d* against the action of a valve spring *e* which is operatively engaged with the valve stem *a'*, all in accordance with 25 established practice. When the cam *d* is in the position illustrated in Figure 1 the valve *a* is lifted from its seat to a maximum extent. The clearance is such as to permit the insertion of the improved grinding element *f*. This element 30 in the form illustrated is so shaped in cross section as to insure intimate engagement of its under face with the valve seat *b* and of its upper face with the working portion of the valve *a*. In cross section, accordingly, the grinding element is generally in the form of a concave disk. 35 Centrally of the grinding element is an opening *f'*. In this embodiment the grinding element is sectional comprising a plurality of segments *f¹*, *f²*, shown as two in number. By a very simple 40 manipulation each segment of the grinding disk can be slid into place under the valve *a* when the latter is raised from its seat as in Figure 1, the central opening *f'* in the assembled disk receiving the valve stem *a'* with the disk disposed coaxially with relation to the valve stem. On one or 45 both faces of the segments of the grinding element is an abrasive surface preferably constituted by sheets of abrasive material *g*, *g'*, attached in such manner as to be removable for re- 50 placement when and as required.

When the cam *d* is in the position indicated in Figure 2 or out of contact with the lifter the spring *e* is effective to urge the working surface of the valve *a* into engagement with the abrasive 55

surface of the disk *f* and, in turn, the under surface of the disk into engagement with the valve seat *b*. In accordance with the invention it will thus be seen that the grinding element is inserted readily into proper working relation to the valve and to its seat without removing the valve or changing the normal relationship of its associated parts. Means are provided for rotating the grinding element to accomplish its intended purpose. Such means may obviously take different forms. That illustrated in the preferred embodiment has the virtue of simplicity and cheapness. As shown in Figure 5 the grinding element is formed with a plurality of radially extending lugs *f*³ at its periphery. A transmission element *h* shown in Figure 4 is provided as a dished generally obverse to the grinding element. The transmission element *h* has a plurality of radially extending lugs *h*' which are adapted to rest between adjoining lugs *f*³ of the segments of the grinding disk. The transmission disk *h* is shown in its operative relation to the grinding disk in Figure 2 where it rests over the valve *a* with its lugs *h*' operatively engaged with the lugs *f*³ of the grinding element. The transmission element *h* is connected operatively through a spindle *i* or otherwise to any suitable source of power. For convenience, this spindle may have a circular flange *i*' and a squared section *i*² adjacent its lower end which is received by a similarly formed hub *h*² on the transmission element *h*. A set screw *h*³ may be employed to secure the transmission element to the spindle *i* as will be apparent. The lower end of the spindle may be tapered as at *i*³ to constitute a centering bearing engageable with the recess *a*² on the axis of the valve.

In operation, it will be apparent that upon application of power through the spindle *i* or an equivalent connection the transmission element *h* is rotated and with it the grinding element *f*. The abrasive material *g* which is in intimate engagement with the working surface of the valve *a* grinds the latter and if the abrasive material *g*' is applied to the under surface of the disk *f* the valve seat *b* is simultaneously ground. The parts are held in proper centered relation by the engagement of the spindle *i*³ with the valve *a*. When the grinding operation is completed the transmission disk *h* is lifted away from its engagement with the grinding element. The valve is elevated by means of the cam *d* and the segments of the grinding unit removed.

As shown in Figure 7 the grinding element is readily adapted to any desired form and dimensions depending on the unit to be ground. In this figure is illustrated a valve *k* having a flat seat *l*. Accordingly, the grinding unit *m* is formed generally as a circular disk with a centrally depressed portion but it need have such a degree of concavity as is shown in Figure 1, where the valve seat and valve are tapered. A grinding surface is interposed between the seat *l* and the flat working surface of the valve. Such grinding surface is accordingly disposed parallel to the face of the seat and the surface of the valve to be ground. In this form the grinding element is of unitary structure and has a radially extending slot *m*' therein to permit the insertion of the grinding

unit between the valve and its seat with the valve stem *k*' disposed substantially concentrically therewith. The same benefits are obtained in that when the valve is raised from its seat the grinding unit can be slipped in readily between the valve and its seat and the abrasive material will be in proper operative relation to the surfaces to be ground. The valve will be urged against the abrasive surface by the valve spring and in both embodiments the tension of the spring can be adjusted if that is found necessary or desirable.

In this figure there is shown by way of example a practical way of securing grinding material to such a grinding element. One sheet of grinding material is indicated at *n* on the upper surface of the grinding element and another grinding sheet is indicated at *n*' on the under surface of the grinding element. These sheets may be circular conforming to the outline of the grinding element and secured in place by upper and lower retaining ribs *o*, *p*, respectively, which engage the grinding sheets and are secured together by removable screws *q*.

In this embodiment as in the one previously described the power transmitter *r* is engageable operatively with the grinding element *m*.

Changes in form, dimensions and details of construction will suggest themselves to those skilled in the art but all such modifications are to be deemed within the scope of the invention so long as there is retained the principle of applying the grinding element to a valve or the like without removing the latter.

What I claim is:

1. A device for simultaneously grinding valves mounted upon valve stems and their associated valve seats and adapted to be used without removing the valve comprising a dished grinding unit having opposed grinding surfaces and an opening therein to receive the valve stem, said grinding unit being formed with a slot extending between the opening and the periphery of the unit to permit the insertion of the unit between the valve and valve seat whereby the valve and valve seat may be ground in a single operation.

2. A device for simultaneously grinding valves mounted upon valve stems and their associated valve seats and adapted to be used without removing the valve comprising a dished grinding unit having opposed grinding surfaces and an opening therein to receive the valve stem, said grinding unit being formed with peripheral lugs and a slot extending between the opening and the periphery of the unit to permit the insertion of the unit between the valve and valve seat whereby the valve and valve seat may be ground in a single operation, and means formed with peripheral lugs to engage the first named lugs to rotate the grinding unit.

3. A device for simultaneously grinding valves mounted upon valve stems and their associated valve seats, comprising a dished grinding unit having opposed grinding surfaces and an opening therein to receive the valve stem, said device being so slotted that it may be applied to the valve and valve seat without removal of the valve from its supporting structure.

FRANK T. SWEIGART.
